CLAIM

The ornamental design for a greeting card, as shown and described.

DESCRIPTION

FIG. 1 is a perspective view of the greeting card showing my new design.

FIG. 2 is a front perspective view thereof; and,

FIG. 3 is a rear perspective view thereof.

All sides not shown in the drawing disclosure forms no part of the claimed design.

The broken lines showing a wine bottle, in FIG. 1, is for illustrative purposes only and forms no part of the claimed design.

1 Claim, 2 Drawing Sheets

FIG. 3
